UNITED STATES PATENT OFFICE.

HERMANN THIELSCHER AND PAUL THIELSCHER, OF BRIEG, GERMANY.

SKATE.

SPECIFICATION forming part of Letters Patent No. 587,768, dated August 10, 1897.

Application filed March 10, 1896. Serial No. 582,572. (No model.)

To all whom it may concern:

Be it known that we, HERMANN THIELSCHER and PAUL THIELSCHER, subjects of the Emperor of Germany, residing at Brieg, near 5 Breslau, Germany, have invented certain new and useful Improvements in Skates, of which the following is a specification.

Our invention relates to skates; and its novel features consist in the arrangement and 10 construction of the devices for fastening the skate to the shoe, which parts are adapted to work entirely automatically.

Our improved skate is adapted to be attached to the shoe by merely placing the foot 15 on the sole-plate of the skate and pushing the foot downward. To this end our improved skate is provided with means enabling the same to stand upright upon the ice, so that the skater merely places his foot on the skate 20 and pushes downward. The skate is also constructed so as to allow of a quick and easy removal from the shoe.

Referring to the drawings which accompany this specification, we have shown our 25 new skate in different constructions, the fundamental principle of the invention, however, being the same in all constructions.

Figure 1 shows a vertical section, and Fig. 2 a bottom view, of the skate without the 30 blade in the locked position. Fig. 3 is a side view of a skate opened and ready to be stepped into. Fig. 4 shows a detail of construction. Fig. 5 is a vertical and Fig. 6 a horizontal section, and Fig. 7 an elevation, of a skate where- 35 in the locking device is located at the heel of the skate, Fig. 8 being a detail of parts at the heel. Fig. 9 is a vertical and Fig. 10 a horizontal section in locked position of a skate 40 wherein the blade itself is used as a locking-lever. Fig. 11 is a detail. Fig. 12 is a sectional elevation of the parts in the unlocked position, and Fig. 13 a detail of certain parts 45 near the toe of the skate. Fig. 14 is a vertical and Fig. 15 a horizontal section of a skate having a somewhat similar arrangement of parts to Fig. 9 and in locked position. Fig. 16 is an elevation of the skate in unlocked 50 position, Fig. 17 being a detail of certain parts near the heel of the skate.

The screw-spindle S carries the nut m, sliding in the groove a of the sole-plate T and bearing the heel-clasp b. The square screw-

head K slides in the wing-key c, revolving in the heel-support p. Said screw-spindle S carries at its other end a cross-head n with 55 double bolts, to which are pivoted on both sides of the blade L the arms o of the knee-levers o and r. The arms r of the knee-lever are pivoted at the front end to the bolt B of the shank of the sole-clasp. 60

The pivot-bolt B slides in the ordinary way in the groove a' of the sole-plate T, and the shanks t t of the sole-clasps are also provided with grooves, so as to move about the guide-bolts E, fixed to the sole-plate T. 65

It is obvious that the sole-clasps will be moved nearer together and the heel-clasp moved backward when the knee of the levers o r is forced upward, and that these parts can be moved in an opposite direction when the knee-lever is moved downward. The movement of the knee-levers o r is effected by means of the levers w w, which are pivoted to the under side of the sole-plate at q q. The arms o of the knee-lever are likewise 75 connected with the levers w w by means of the pin N, moving in the slot A.

To the inside of the forward ends of the levers w w, which are made of elastic material, are pivoted the shanks of the locking 80 devices y. The upper ends of the locking-pieces y are securely fastened together by means of a rivet-bolt z. The other ends of these devices grasp under the levers w w by means of their outwardly-bent extremities 85 f f for the purpose of lifting these levers out of the supporting-points x x, which are arranged in the closing-piece V, secured to the sole-plate T. These supporting-points are in the shape of recesses x x, the lower part 90 of the piece V being in the form of a head k, as shown. The locking devices y lie under this head and somewhat open. When the hook-shaped clasp of the ends of such device is pressed downward, the head k enters between like a wedge and the levers w w are forced apart until they can slide sidewise down the head k. 95

To the levers w w are connected the arms w', which are pivoted at G and which are secured both in a parallel and a perpendicular position by the spring M. 100

The spring R, securing the flap P in its closed position, extends under the sole-plate

T and here rests upon the screw-spindle S. Any possible backward motion of the screw-spindle S, when the skate is open, Fig. 3, and consequently the locking of the skate, is 5 thereby prevented.

When using the skate, the levers *w w* must be first locked. The sole-clasps are then drawn apart from each other by the hand so far that the shoe to which the skate is to be 10 fixed can be placed between the clasps. Then by turning the wing-key *c* the heel-clasp *b* is displaced sufficiently to allow the heel to conveniently enter. The shoe must now be placed on the sole-plate and the screw-spindle 15 S turned until the heel-clasp abuts against the shoe-heel, whereupon (by further turning) the screw-spindle S, together with the cross-head *n*, the jointed levers *o r*, the pivot-bolt B, and the shanks of the sole-clasps *t*, sliding 20 along the studs E, are forced forward and the sole-clasps close themselves. When the 25 skate is set tight, the wing-key *c* is fixed in the ordinary way by means of the elastic flap P, one of the wings of the key being held in a groove provided in said flap.

For removing the skate it is sufficient to push down the hook-shaped part of the locking device *y*, whereby the levers *w w* are lifted from their rests *x x* and moved in a downward 30 direction. Hereby the knees of the levers *o r* are moved downward also, and the skate is opened. To refasten, the arm *w'* must be folded downward. The shoe can then be placed thereon, as the skate is sufficiently 35 supported by the said arm and the end of the blade. The open skate is then stepped on, whereby the closing-levers *w w* are forced in their rests *x x*, it being understood that the arms *w'* are longer than the height of the 40 blade. As the levers *w w* are forced upward the jointed levers *o r*, which are connected with the same, are straightened and the clasps firmly pushed against the shoe. Finally the 45 arm *w'* is closed against the foot by sliding forward.

Figs. 5, 6, 7, and 8 represent a skate similar to the construction above described, the only difference being that the locking device is located at the heel end of the skate. In 50 this construction the free ends of the levers *w w* are located under the heel part of the skate. The groove *a'*, in which the pivot-bolt B of the arms *t' t'* of the sole-clasp slides, is placed more to the middle of the sole-plate T. 55 The arms *t' t'* of the sole-clasps and the slots in the same run in a direction toward the forward part of the skate. The rests *x' x'* are arranged on both sides of the heel-supports *p'* close under the sole-plate T. The levers *w w* 60 are for safety's sake provided with curved parts *z z*. The free ends of the levers *w w* are bent outwardly behind the heel part of the skate, and to these are pivoted the shanks of the locking devices *y'*. They do not slide 65 along the heel-support *p'*, serving as a closing-piece, but on the piece *k*, fixed under the heel and similar to the head of the above-de-

scribed closing-piece V, Fig. 4. The movement of the locking devices *y'* is limited with respect to the levers *w w* by the pins *f f* 70 passing over the upper surface of the device. The skate is adjusted in the same manner as described before.

In Figs. 9, 10, 11, 12, and 13 a skate is represented in which the blade itself is used as 75 a locking-lever, and for this purpose the sole-plate and blade are not rigidly connected.

The construction of the skate, as shown in the drawings, is as follows: The jointed connection between the sole-plate T and the blade 80 L is obtained by the heel-support *p*³, which is rigidly attached to the sole-plate T, being pivoted at *s* to the blade L. The swinging distance of these pivoted parts attached to each other is determined by the size of a slot *q*³, 85 arranged in the body of the blade, in which slides the stud *f*³, fastened to the heel-support *p*³. The pivot-bolt B of the arms *t' t'* of the sole-clasp is connected with the end of the cross-head *n*², fastened to the screw-spindle 90 S by means of the knee-levers *o' r'*. The arms *r'* are extended over the knees and bent down outwardly. These extensions, serving as supports to the open skate, are indicated in the accompanying drawings by the letter *w'*. 95 The blade L is connected with the sole-plate T in the manner below described. The connecting-piece *u* consists of two flat strips arranged at both sides of the forward support of the sole-plate and provided with slots *e*, 100 moving about studs *z*⁵. The forward end of the piece *u* is pivotally connected with the locking device *y'*. The rear end of the connecting-piece is cut obliquely and rests in a box V, fastened to the blade L and which 105 forms the middle support of the sole-plate T. A hook *x*³, fastened to the sole-plate T, extends in the box and is adapted to hold the end of the piece *u*. In the side walls of the 110 box V are formed the slots A, in which the studs N of the arms *o' r'* slide. The movable connection of the blade L, serving as closing-lever, with the knee-levers *o' r'* is thus obtained. The foremost support of the sole-plate has a projection *h* corresponding with 115 a hole in the sole-plate T. The connecting-piece *u* is normally held in the box V by means of a spiral spring F.

The use of this skate is as follows: After 120 the sole and heel clasps have been fastened to the shoe in the same way as in the skates previously described the locking device *y'* is forced down. The connecting-piece *u*, under the action of the spiral spring F, is drawn back, and the end of said piece *u* is drawn 125 out of the hook *x*³. The blade L is then turned downward at the pivot-bolts *s*. Hereby the knee-levers *o' r'*, connecting with the blade by means of the stud N in the slots A, are likewise forced downward. The joint of 130 the same is likewise drawn down and the sole-clasps and heel-clasps are removed from the shoe. The latter can then be removed from the sole-plate.

The skate finds a sufficient basis of support to enable it to stand upright in the sidewise-bent supporting-arms w^4 and the blade. To refasten the skate to the shoe, it is simply necessary to tread on the sole-plate T. Hereby the hook x^3 enters into the box V, thereby acting upon the obliquely-cut head of the connecting-piece u, which is pushed back. When the hook x^3 is forced sufficiently far into the box, the piece u, under the action of the spring F, automatically enters into the hook and in such a manner brings about the rigid connection of the sole-plate and the blade. In closing the skate the knee-levers $o^2 r^2$ must be extended and the clasps holding the shoe are forced against the same, as described.

In Figs. 14, 15, 16, and 17 is represented a skate which is similar to the one above described, but the closing mechanism is here located under the heel part. The difference in this skate and the one above described is as follows: The sole-plate T and the blade L are connected at the forward end by a pivot s^3 . The middle support D consists of two parts, one half, D', being fastened to the blade L and the other half, D, to the sole-plate T. The two parts are surrounded by a strong spiral spring M, which holds the supporting halves together and continually forces the sole-plate T and the blade L apart. The screw-spindle S lies with its head K⁴ under the middle of the sole-plate T. The screw-threaded end, together with the cross-head fitted with double studs, is placed in the direction of the heel. The pivot-bolt B³ and the arms t² of the sole-clasps are similarly constructed, as shown in Figs. 5 to 8. The arms of the knee-levers $o^3 r^3$ are extended beyond their knees. These extensions of the arms o^3 are provided with slots A³. By these slots the lever-arms o^3 are guided by the bolt N³, which is placed in the heel-support p⁴. In the same manner the connecting-piece u' is guided by the bolt N³, which passes through a slot of the piece located in the support p⁴. The hook x⁴ is fixed to the sole-plate T above the piece u'. The opening of the piece u' occurs under the influence of an angular lever y⁵, pivoted at z' to a flap-shaped contrivance of the heel-support p⁴. The lever y⁵ acts upon the piece u' by means of a slot in the bolt catching the piece. The spiral spring F forces the lever y⁵ and the piece u', respectively, always into the locking position. The fastening and loosening of the

skate are effected in a similar manner as is the 55
skate described under Figs. 9 to 13. By moving the lever y⁵ in a downward direction the piece u' is drawn, as shown, out of the hook x⁴, whereupon the sole-plate T and the blade L are forced apart by the pressure of the spiral spring M and turn around the pivot s³. The skate now opens, as, owing to the parting of the sole-plate T from the blade L next to the heel parts, the lever-arm o³, which is connected with the heel-support p⁴, resting 60
on the blade L, and consequently also the lever-arm r³ and its extensions w⁴, which are bent downward, are forced downward, whereby the clasps of the skate are separated. The skate can in this condition be put on, as 70
sufficient supporting-points exist in the blade L and the arms w⁴. If the foot be now placed upon the open skate, the sole-plate T is turned downward after a compression of the spiral spring M. The hook x⁴ presses on the obliquely-cut head of the piece u', whereby the latter is pushed back until it can spring into the opening of the eyelet under the impulse of the spiral spring F. By the approach of the sole-plate T and the blade L the lever-arms o³ are raised, together with the lever-arms r³. The knee-levers o³ r³ are extended, and thereby the drawing in of the sole and heel clasps to the shoe is effected.

Now, having described our improvements, 85
we claim as our invention—

1. The combination in a skate-fastening, of a knee-lever o, r, a lever w for operating the said knee-lever, and supports w' pivoted on said lever w, and a spring-lock adapted to 90
hold the supports w' both in its upper and lower positions, substantially as described.

2. The combination in a skate-fastening, of a knee-lever o, r, a lever w for operating said knee-lever, a screw S for pushing the knee- 95
lever, sole-clamps t, a pivot for said sole-clamps t adapted to move longitudinally on the skate and operatively connected with said knee-lever, and heel-clamps operatively connected with said screw, substantially as de- 100
scribed.

Signed at Breslau, Germany, this 7th day of January, A. D. 1896.

HERMANN THIELSCHER.
PAUL THIELSCHER.
